(57) **CLAIM**

We claim the ornamental design for a reagent set, as shown and described.

DESCRIPTION

FIG. 1 is a front and top perspective view of a reagent set of the present invention;

FIG. 2 is top view thereof;

FIG. 3 is a bottom view thereof;

FIG. 4 is a front view thereof;

FIG. 5 is a rear view thereof;

FIG. 6 is a first side view thereof; and,

FIG. 7 is a second side view thereof.
